UNITED STATES PATENT OFFICE.

GEORGE W. COBEL, OF BROOKINGS, SOUTH DAKOTA.

MAILING-CARD.

1,213,748.

Specification of Letters Patent. Patented Jan. 23, 1917.

Application filed April 27, 1916. Serial No. 94,027.

To all whom it may concern:

Be it known that I, GEORGE W. COBEL, a citizen of the United States, residing at Brookings, in the county of Brookings and 5 State of South Dakota, have invented certain new and useful Improvements in Mailing-Cards; and I do hereby declare the following to be a full, clear, and exact description of the invention, such as will enable 10 others skilled in the art to which it appertains to make and use the same.

This invention relates to mailing cards for deposits, and has for an object to provide a card embodying new and improved 15 means for receiving and accommodating coins, currency, checks, and other negotiable paper, together with improved means for retaining such deposits in and on the card, and with means accompanying the card for 20 disclosing the contents to the recipient.

A further object of the invention is to provide a card properly proportioned to be mailed in an ordinary envelop, having improved means for receiving and retaining 25 various forms of money and negotiable instruments, with deposit slips in duplicate interlaid by a carbon sheet whereby the depositor may make duplicate memoranda of the deposits, one of which is retained by himself 30 and the other forwarded to the receiving institution together with the deposits.

With these and other objects in view the invention comprises certain novel features of construction, combination and arrangement of parts as will be hereinafter more 35 fully described and claimed.

The drawing discloses in plan one of the improved cards with the flaps spread out in position to receive the coins and other 40 deposits, and showing the deposit slips, one of which is torn away showing the carbon sheet beneath also partly torn away to disclose the deposit slip below.

In the specific embodiment of the invention shown in the drawing a card 1 is employed of such dimensions as to be received in a usual and ordinary envelop, and provided in its left half with a plurality of 45 openings 2 of proper sizes to receive coins of various denominations. To the back of the card is applied a sheet 3 as of paper or the like, and where it covers the coin receptacles it forms a rear wall thereof. This sheet is cut into such shape that it forms 50 three flaps projecting beyond the contour of the card at its left portion, and which I will

respectively call the small flap 4, the large flap 5, and the sealing flap 6. Where these flaps join the body of the sheet which is along the edge of the card, they may be 60 scored or otherwise provided with fold lines 4', 5' and 6' respectively, and no flap has any gum contiguous to its fold line. The other three margins of the small flap are 65 gummed as seen at 7, the three margins of the large flap are gummed as seen at 17, and the three margins of the sealing flap are 70 gummed as seen at 27. This flap may well be provided with outstanding ears 8 beyond its outer edge, and the faces of these ears 75 are gummed as at 9 along the outer line of gum 27'.

Upon one end of the card a deposit slip 10 is secured with a carbon sheet 11 overlying such deposit slip 10, and a second deposit 80 slip 12, in all respects similar to the deposit slip 10, is superposed upon the carbon sheet 11 and provided with the necessary or desirable data, forms and blanks for filling in the deposits carried by the card.

In the use of this improved device, the 85 coins are first inserted into receptacles 2, and currency or checks or other negotiable paper may then be laid upon the coins in folded condition. The gummed margins of the small flap 4 are now moistened and the entire flap laid over the deposits whatever they are. The gummed margins of the large flap 5 are now moistened and the entire flap is 90 carried transversely across the small flap 95 and its side margins sealed thereon whereas its end margin 17' projects beyond the right hand side margins 7' of the small flap and is sealed directly on the card at about the point indicated at 17''—thus sealing the large flap onto the small one and also sealing 100 the large flap onto the card and therefore holding the contents very reliably in place. Finally the margins of the sealing flap 6 and its ears 8 are moistened, and this flap is laid over onto the large flap and sealed down onto the same. It will be observed that the transverse width of the sealing flap is about 105 the same as the transverse dimension (length) of the large flap, whereas the latter dimension is greater than the transverse width of the small flap as has been explained. The result is that the deposit is entirely surrounded by at least two thicknesses of paper gummed to each other or to 110 the card, and on three sides by the fold lines; and loss of this deposit in transit

through the mails is almost impossible. These several flaps and the bills or other negotiable paper, if any make a considerable thickness at this the left end of the card, 5 but the thickness is offset by that of the tablet or pad of deposit slips at the right end of the same, and therefore the entire device may be said to be substantially of one thickness throughout.

10 The deposits slips are filled in to show the amount of deposits for the various items, and the top slip and carbon sheet removed, leaving the deposit slip 10 secured to the card which, together with its contents, is 15 now inserted in an envelop and mailed to the depository.

For convenience in operating and to be sure that the flaps are properly folded, the flaps are preferably numbered flap 1, flap 2 20 and flap 3, as shown in the drawing, which will indicate the sequence in which such flaps should be folded over.

While it is intended that the card shall be employed for mailing deposits to banks 25 and other deposit-receiving institutions it is obvious that the principle involved is not limited to making deposits, but may be employed with equal efficiency where coins, cur-

rency or the like are to be mailed for any purpose.

I claim:—

The herein described mailing card comprising a body of cardboard provided at its left end with a series of coin receptacles, a memorandum pad attached to the face of the 35 card at its right end, a sheet attached to the back of the card and closing said receptacles at one side, and three flaps integral with the edges of the sheet and projecting beyond the edges of the card at its left end and beyond 40 the left extremity of the card, all flaps being gummed around the three margins remote from the card and one flap being narrower transversely than the end flap is long 45 so that when the former is folded over the coin receptacles and onto the card the latter may be folded across the first flap and gummed upon it and directly to the face of the card between said receptacles and pad.

In testimony whereof I affix my signature 50 in presence of two witnesses.

GEORGE W. COBEL.
